UNITED STATES PATENT OFFICE.

HUGO LENTZ, OF HALENSEE, GERMANY, AND CHARLES BELLENS, OF NEUILLY-SUR-SEINE, FRANCE.

FLUID-PRESSURE ENGINE.

No. 877,847.

Specification of Letters Patent.

Patented Jan. 28, 1908.

Application filed April 28, 1906. Serial No. 314,124.

To all whom it may concern:

Be it known that we, HUGO LENTZ, a subject of the German Empire, and resident of 123 Kurfürstendamm, Halensee, near Berlin, 5 in the Empire of Germany, engineer, and CHARLES BELLENS, a subject of the Kingdom of Great Britain, residing at 43 Rue de Chézy, Neuilly-sur-Seine, in the Republic of France, have invented certain new and useful 10 Improvements in and Relating to Fluid-Pressure Engines, of which the following is a specification.

This invention has for its object a method of and the means for obtaining in elastic 15 fluid machines simple or multiple expansion running by rendering the cylinders solid one with the other in groups of two.

It consists in establishing between these 20 combined cylinders communications such that the concordant phases of admission or exhaust may be controlled by a single valve member and that consequently the two cylinders rendered solid, instead of expanding from one to the other as in compound engines, work at the same pressure.

In the accompanying drawing, several constructional forms of steam cylinder to which the invention has been applied are illustrated by way of example.

30 Figure 1 is a diagrammatic view of a group of two cylinders, showing clearly the communications established between these cylinders. Fig. 2 shows a constructional form of Fig. 1. Fig. 3 represents another constructional form in which all the valve members are situated at the same end of the cylinders. Fig. 4 represents a section on the line 4-4 of Fig. 3. Fig. 5 is an external plan view of Fig. 3. Fig. 6 is a perspective view. Figs. 7 and 8 show the application to the invention of distributing valves of various kinds. Fig. 9 shows a driving axle for the application of the invention to a locomotive. Fig. 10 is a plan view showing 45 the grouping of the four cylinders.

In engines comprising several cylinders working at the same admission pressure, each cylinder has its own valve gear. In order to couple the cylinders the plan hitherto adopted is compounding, that is to say the known cascade arrangement of cylinders.

50 The present invention permits of rendering solid in an engine, in groups of two, cylinders working at the same pressure, by connecting them one with the other by suit-

able passages such that the concordant phases of admission or exhaust, may be controlled by a single valve member.

Fig. 1 shows diagrammatically the communications between the cylinders *a* and *b* and a method of grouping the valve members upon the same. One steam admission passage *c* serves for the two cylinders and also the boxes of the admission valves *f*, *g*. One discharge passage *h* serves for the two cylinders and also the boxes of the exhaust valves *d*, *e*. A communication passage *i* connects the box of the admission valve *f* (cylinder *b*) with the box of the exhaust valve *e* (cylinder *a*). Finally a conduit *k* establishes communication between the box of the admission valve *g* (cylinder *a*) and the box of the exhaust valve *d* (cylinder *b*). The passage *i* communicates by means of a port *m* with the interior of the cylinder *b* and by means of a port *n* with the interior of the cylinder *a*. In the same way the passage *k* communicates by means of the port *o* with the interior of the cylinder *a* and by the port *p* with the interior of the cylinder *b*.

The operation is as follows: Assuming the admission valve *f* to be open and consequently the admission valve *g* closed; the steam in the passage *c* passes the member *f* (open) into the passage *i* and through the ports *m* and *n* into the cylinders *b* and *a* in order to impel the pistons in inverse directions. Obviously therefore, in this way a single valve *f* controls the admissions to the two cylinders *b* and *a*. During this period of admission, the exhaust valve *d* of the cylinder *b* is open, the exhaust steam of the cylinder *b* escapes through the port *p*, passes the exhaust member *d* (open) into the exhaust passage *h*. At the same time the exhaust steam from the cylinder *a* issues through the port *o*, passes through the communication passage *k* and passes the exhaust valve *d* into the common exhaust passage *h*. Again, therefore, a single exhaust valve controls the exhaust of the two cylinders. The same operation is repeated for the inverse stroke of the pistons, with this difference, however, that it is the admission member *g* and the exhaust member *e* that are operative.

The constructional form represented in Fig. 2 reproduces this disposition of the connections with this difference that, in order to simplify the construction, certain passages

and communications, shown separately in Fig. 1 for the sake of clearness, are superposed or placed side by side. This constructional form comprises valves as operating members.

In the constructional form in Figs. 3 to 6, all the valve members are arranged on the same end of the cylinder and they correspond to two admission openings for steam r , s and a common exhaust passage t (Figs. 5 and 6). The admission valves are designated u and v , the exhaust valves x and y . The communications between the two cylinders a and b comprise a passage 1 which establishes communication between the boxes of the valves u and x and the cylinder b ; this passage communicates respectively with the cylinders a and b by the ports 2 and 3. A passage 5 (which is more clearly shown in Fig. 4) establishes communication between the box of the valves y and v and the cylinder a . This passage communicates with the interior of the cylinders b and a by way of the ports 6 and 7, respectively.

By reference to Fig. 4 it will be seen that the crossed passages 1 and 5 for communication between the two cylinders, are superposed and that the two cylinders present a common exhaust box 8 which comprises the exhaust outlet t .

The operation is the same as in Fig. 1, except that the steam is admitted through two inlets. It will of course be understood that the valves may be replaced by any other appropriate distributing members, for example of the Corliss type (Fig. 7) or a piston valve (Fig. 8). It is also possible to employ members effecting both the admission and exhaust. Again, a single slide valve would suffice for the two cylinders, and it might be arranged at the junction of the passages, for example.

Regarding Figs. 3 and 5 as representing as a whole a four-cylinder engine, it will be seen that the cylinders are in line. It should be clearly understood that these cylinders which are thus combined may be arranged in steps, or in tandem or grouped in any other way permitting of the application of the invention. It is also possible in an engine comprising several groups of cylinders, to combine high pressure groups and low pressure groups respectively.

The advantages are as follows: The result of combining cylinders working at the same pressure and therefore having the same dimensions, is to perfectly balance all the moving masses such as pistons and external transmission gear. The construction and more especially the casting of the cylinders is more readily and more economically effected, seeing that the number of valves is reduced to the minimum and that consequently the operating and transmission gears are likewise simplified. It will also be noticed

that in the constructional forms represented, the cylinder bodies are entirely independent one of the other, as regards local expansions.

The invention is especially applicable with great advantage to locomotives upon which engines it permits of obtaining the balancing necessary for running efficiently at great speeds and of turning to account the advantages of superheating.

Assuming, for example, that the cranked shaft represented in Fig. 9 is the driving axle of a locomotive, it will be seen that the cranks of one combined group of two cylinders are keyed at 180° relatively to each other, as are also the cranks of the second group of two cylinders, which latter are however displaced by an angle of 90° relatively to the first group. This arrangement insures the necessary balancing of the moving parts. The simplification of the transmissions also results in considerably diminishing the risk of damage in running. The cylinders may be arranged entirely between the wheels, or partly inside and partly outside the wheels, or all the cylinders may be arranged outside the wheels.

For the application to locomotives the constructional form illustrated in Figs. 3 to 6 may be adopted, in which all the valve members are situated at the front end of the cylinders and in the front of the engine, which arrangement facilitates access for inspection repair and replacement.

The invention is applicable in a general way to elastic fluid engines, driving or being driven and other machines such as steam engines, compressor pumps and gas motors.

Having now particularly described and ascertained the nature of our said invention and in what manner the same is to be performed, we declare that what we claim is:

In a fluid pressure engine, two groups of two double-acting cylinders, the cylinders of each group having cranks displaced through 180° to each other and through 90° to the other pair of cranks in the other group, ports at each end of the cylinders, crossed passages in each group of cylinders, connecting the ports at one end of the cylinders with the ports at the opposite end of the other cylinder of the same group, an admission passage c and an exhaust passage h , admission members f , g , connecting the ports at one end of each cylinder with the admission passage c , and exhaust members d , e , connecting the ports at the other end of each cylinder with the exhaust passage h .

In testimony whereof we have hereunto placed our hand and seal at Milan, Italy this twelfth day of April 1906.

HUGO LENTZ. [L. S.]
CHARLES BELLENS. [L. S.]
